UNITED STATES PATENT OFFICE

NELS H. SANDBERG, OF MINNEAPOLIS, MINNESOTA, ASSIGNOR TO WALDORF PAPER
PRODUCTS COMPANY, OF ST. PAUL, MINNESOTA, A CORPORATION OF MINNESOTA

BOX CRUSHER

Application filed July 8, 1929. Serial No. 376,797.

My invention relates to box crushers and has for its object to provide a box crusher employing a pair of belts arranged in converging relation with respect to one another, both 5 of said belts being driven in a direction toward the locality of convergence thereof.

Another object of the invention resides in arranging one of said belts in a substantially horizontal position and in disposing the 10 other of said belts in superimposing inclined position above said first named belt.

Another object of the invention resides in providing a framework straddling said first named belt, said framework having a portion 15 superimposing said belt and in mounting for rotation in the superimposed portion of said framework a shaft, and in further pivoting to said shaft a sub-frame having a second shaft journaled in the lower end thereof, 20 said sub-frame being movable toward and from said first named belt, said shafts having rollers mounted thereon adapted to carry said second named belt.

An object of the invention resides in 25 weighting the lowermost roller to force the lower portion of the second belt toward the first belt.

A still further object of the invention resides in providing an auxiliary roller for 30 taking up the tension in said second belt, said auxiliary roller being pivoted to the shaft at the lower end of said sub-frame and serving further to add to the weight on the lower end of said second belt.

Another object of the invention resides in 35 providing resilient means for retarding movement of the free end of said sub-frame upon the arrival of said second belt at the surface of said first belt.

A still further object of the invention resides in constructing the superimposed portion of said framework with a pair of longitudinal frame members lying along each side 45 of said belts and with a third longitudinal frame member disposed outwardly from one of said first named longitudinal frame members, and in mounting upon said last two longitudinal frame members a motor.

An object in the invention resides in positioning across said last two frame members

a counter shaft driven by said motor, and a jack shaft driven from said counter shaft.

A still further object of the invention resides in extending across the longitudinal frame members positioned adjacent each side 55 of said belts another counter shaft and in providing a drive from said jack shaft through said second counter shaft and to said second roller shaft.

An object of the invention resides in providing a separate drive from said jack shaft 60 for said first named belt.

A feature of the invention resides in providing the drive for said second named roller shaft with a revoluble member concentric 65 with the first named roller shaft.

Other objects of the invention reside in the details of construction thereof and in the novel combination and arrangement of parts hereinafter illustrated or described. 70

In the drawings:

Fig. 1 is a plan view of a box crusher illustrating an embodiment of my invention.

Fig. 2 is a side elevational view of the structure shown in Fig. 1. 75

My invention proper comprises primarily two belts 10 and 11 which are supported upon a suitable frame structure A, said belts being constructed and supported in the manner customary with ordinary endless traveling conveyors. The belt 11 may be a portion of a traveling conveyor and such device being well known in the art has only been partly illustrated in the drawings. This belt consists of a lower run 12 and an upper run 13 so which passes over a suitable roller 14 mounted upon a shaft 15 journaled in bearings attached to the said frame structure. 85

The frame structure A consists of a number of uprights 16, 17, 18, 19, 20 and 21 which 90 are connected together at their lower ends by means of angles 22 serving as base members for supporting the same in upright position and for tying the said uprights together. These uprights have attached to them, intermediate their ends, longitudinal frame members 23 and 24 which are securely riveted thereto and which form a rest for a transversely disposed plate 25 positioned therebetween and extending from the up- 100

right 16 to the upright 18. The upper run 13 of the belt 11 rests directly upon this plate which forms a suitable support for preventing the same from sagging intermediate its ends. The plate 25 may be further reinforced by means of cross angles 26 secured to the angles 23 and 24. The uprights 16, 17, 18, 19, 20 and 21 straddle the belt 11 and the uprights 16, 17, 19 and 20 extend upwardly above the said belt as best shown in Fig. 2. To the upper ends of these latter uprights is attached a superstructure comprising three longitudinal frame members 27, 28 and 29 which are attached to two transverse frame members 30 and 31. The uprights 16, 17, 19 and 20 are preferably in the nature of channels and have secured to the flanges thereof short clip angles 32 which have the flanges of the same facing in the opposite direction from the webs of the said uprights and to which the two longitudinal frame members 28 and 29 are rigidly secured. The cross frame members 30 and 31 may be channel shaped beams and rest directly upon the longitudinal beams 27, 28 and 29.

For supporting the protruding ends of beams 30 and 31 two additional uprights 33 and 34 are employed which are riveted to the ends of said beams and which extend down to the surface on which the uprights 16 to 21, inclusive, rest. Where the device is installed adjacent the wall of the building the uprights 33 and 34 may be positioned adjacent such wall, or brackets or other suitable structures used in place thereof.

The shaft 15 supporting the roller 14 is journaled in two bearings 35 and 36 attached to brackets 37 mounted on the uprights 18 and 21. These bearings are rigidly secured to the said brackets and support the roller 14 in a position to bring the upper run 13 of belt 11 upon the top of the plate 25 so that all of the pressure imparted to the said belt in the crushing of said boxes is taken up by the said plate and the supporting structure therefor. The other end of the belt 11 is similarly mounted on a roller not shown, and additional supports intermediate the ends of the plate may be provided similar to the plate 25, or suitable supporting rollers placed at proper intervals may be used in lieu thereof and in lieu of the plate 25, if preferred. The angles 23, 24 besides supporting the plate 25 and the upper run 13 of belt 11 also serve to retain the upper run of said belt in lateral position with respect to the frame structure of the invention.

The upper belt 10 is supported as follows: Across the two longitudinal frame members 27 and 28 and adjacent the uprights 16 and 19 extends a shaft 38. This shaft is journaled in two bearings 39 and 40 attached to said frame members. Upon this shaft is mounted a roller 41 which may be keyed to the said shaft or which may idle upon the

same, as desired. Straddling roller 41 is a forked member 42 which is constructed with two arms 43 and 44 connected by an intermediate portion 45 and terminating in bearings 46 and 47 journaled on the shaft 38 adjacent the bearings 39 and 40. The forked member 42 is constructed with a number of lugs 48 issuing outwardly therefrom to which are secured a number of longitudinal frame members 49 forming in conjunction therewith a sub-frame which I have indicated in its entirety at 50. The other ends of the longitudinal frame members 49 are similarly connected to a forked member 51 which is constructed with arms 52 and 53 and an interconnecting portion 54 similar to the arms 43 and 44 and the interconnecting portion 45 of the forked member 42. The arms 52 and 53 terminate in bearings 55 and 56 similar to the bearings 46 and 47 which journal another shaft 57. The shaft 57 has mounted on it a roller 58 similar to the roller 41 which is keyed to the said shaft for a purpose to be presently described. The belt 10 passes around the two rollers 41 and 58 and is carried thereby. The longitudinal frame members 49 have attached to them along the under sides thereof a plate 59 similar to the plate 25 of belt 11 which plate lies in close proximity to the lower run 60 of belt 10, the upper run 61 thereof being free. This plate together with the frame members 49 assists in taking up the stress imparted to the belt 10 when the boxes are being crushed. It is to be noted that the sub-frame 50 and other parts mounted thereon are supported solely upon the shaft 38. By means of this construction it will readily become apparent that such structure is swingable bodily upon the shaft 38 to cause the free end of belt 10 to move toward and from belt 11. When the parts are disposed in normal position the two belts 10 and 11 converge toward one another as indicated in full lines in Fig. 2.

For tightening the belt 10 an auxiliary roller 62 is employed. This roller is journaled in two bearings 63 and 64 which are attached to the ends of two arms 65 and 66. Arms 65 and 66 terminate at their other ends in other bearings 67 and 68 which are pivoted upon ends of the shaft 57 adjacent the bearings 55 and 56. The roller 62 is preferably weighted and when positioned as shown in Fig. 2 exerts a downward pressure upon the upper run 61 of belt 10 which causes said belt to snugly hug the two rollers 41 and 58 so as to effect the drive of the said belt upon the rotation of one of said rollers.

For driving the various belts forming portions of my invention, I employ an electric motor 69 which is mounted upon two short beams 70 and 71 attached to the longitudinal frame members 28 and 29. This motor is positioned intermediate the ends of the said frame members and the shaft 72 thereof has

attached to it a sprocket wheel 173 from which the belts of the invention are driven. Forwardly of the motor 69 is disposed a counter shaft 73 which extends across the frame members 28 and 29 and which is journaled in two bearings 74 and 75 secured thereto. This shaft carries a sprocket wheel 76 which is driven from the sprocket wheel 173 on motor shaft 72 through a sprocket chain 77. Forwardly of shaft 73 is disposed a jack shaft 78 which similarly extends across the frame members 28 and 29 and which is journaled in bearings 79 and 80 attached to the longitudinal frame members 28 and 29. This jack shaft has secured to it a spur gear 81 which meshes with a spur pinion 82 fast on the shaft 78. It will be noted that the sprocket 76 is considerably larger than the pinion 78 and likewise the gear 81 is considerably larger than the gear 82 so that the shaft 78 travels at a substantially reduced rate of speed as compared with the motor shaft 72.

The belt 11 is driven through the roller 14 directly from the jack shaft 78. This is accomplished as follows: Upon the end of the shaft 15 is attached a sprocket wheel 83 while on the shaft 78 is attached another sprocket wheel 84 in alignment with the sprocket wheel 83. A chain 85 passes over these two sprockets and gives the shaft 15 a clockwise rotation when viewed as shown in Fig. 2 to cause the upper run 13 of belt 11 to move in the direction of the arrow.

The belt 10 is driven from the jack shaft 78 in the following manner: Across the two frame members 27 and 28 extends a transverse shaft 86 which is journaled in two bearings 87 and 88 attached to said frame members. This shaft has secured to it a sprocket wheel 89 while the shaft 78 has similarly secured to it a sprocket wheel 90 aligning with said first named sprocket wheel. A sprocket chain 91 passes over both of these sprocket wheels and drives the shaft 86 from the shaft 78 in the same direction of rotation as said shaft 78. The shaft 38 previously referred to as supporting the roller 41 and the upper end of the sub-frame 50 extends outwardly beyond the bearing 39 and supports thereon a spur gear 92 and a sprocket wheel 93. These two members are rigidly connected together and rotate idly upon the said shaft, said members being retained in place thereon through a collar 94. The spur gear 92 meshes with another spur gear 95 on the end of shaft 86 giving the sprocket wheel 93 a counter clockwise rotation. The shaft 57 which supports the lower roller 58 also extends outwardly beyond the bearings 56 and 68 and has attached to it a sprocket wheel 96 aligning with the sprocket wheel 93. A chain 97 passes over both of these sprocket wheels and drives the roller 58 from the sprocket wheel 93 which causes the said roller to also travel

in a counter clockwise direction making the lower run 60 of belt 10 travel in the direction shown by the arrow in Fig. 2. The sprocket wheel 93 being mounted upon the same shaft on which the sub-frame 50 is pivoted permits of swinging said sub-frame from its lowermost position as shown in full lines in Fig. 2 to its uppermost position, as shown in dotted lines at 98 in the same view without affecting the driving of the roller 58 and the belt 10.

In the operation of the device, paper boxes and similar articles formed of paper which are ordinarily in clumsy and awkward form, are placed on the upper run 13 of belt 11. As the said belt continues to travel in the direction of the arrows the boxes become wedged in between the said run of belt 11 and the lower run 60 of belt 10. This has the effect of crushing and flattening the boxes when they reach the converging portions of the said belts. The belt 10 normally lies close to the belt 11, the end rollers 58 and 14 thereof being superimposed. As the flattened boxes reach the converging portions of these belts, the entire sub-frame 50 together with the belt 10 and the other appurtenances connected therewith are bodily swung about the shaft 38 as a pivot, causing the flattened box to be discharged between said belts at the discharge ends thereof designated at 99 in Fig. 2. For the purpose of providing sufficient force for flattening the boxes the roller 58 which is preferably constructed of sheet metal, may be weighted by filling the same with concrete or any other suitable substance. The roller 62 may likewise be weighted to cause the same to produce a proper tension in the belt, at the same time assisting in forcing the sub-frame 50 downwardly.

For the purpose of reducing the movement of the belt 10 toward the belt 11 when nearing the position thereof shown in Fig. 2, I employ a resilient member which I have designated at 100. This member is preferably in the nature of a coil spring and is retained within a cage or framework 101 preferably attached to the ceiling 102 of the building in which the device is installed or to any other suitable superstructure. The spring 100 rests upon a seat 103 formed on the cage 101 which has extending through it a bolt 104 formed at one end with an eye 105 and threaded at its other end to receive a nut 106. Upon the other end of the spring 100 is mounted a cupped washer 107 which bears against the said spring and against the nut 106 of bolt 104. Upon drawing the bolt 104 downwardly the spring 100 is compressed. The eye 105 of bolt 104 has attached to it two cables 108 which are secured to eyes 109 and 110 attached to the bearings 55 and 56. The tension on the spring 100 is regulated through the length of the cables 108 and nut 106 to cause the said spring to

exert an upward force on the sub-frame 50 when the same is in its lowermost position. As soon as the sub-frame travels upwardly a short distance the tension of the spring 100 is released and slack occurs in the cables 108 which causes all of the weight of the said sub-frame and rollers attached thereto to be effective in crushing the boxes and other structures entering in between the two belts 10 and 11. As the boxes leave the discharge end 99 of the box crusher the spring 100 serves to slacken the return movement of the sub-frame 50 to prevent injury to the various parts of the apparatus.

15 My invention is highly advantageous in that a simple and positive device is provided which will quickly and effectively crush paper boxes in a manner to flatten and compact the same. The device will operate upon 20 any box or similar structure not exceeding the maximum spacing between the two belts thereof. In the event of the box being of too rigid character to be crushed by the device, the same will pass completely through the 25 crusher without injuring any of the parts thereof or without stopping the device or rendering the same otherwise inoperable. The crushing effect upon the boxes progressively increases so that a minimum amount 30 of power is required for operating the device, thereby permitting the running of the belts at a greater rate of speed than would otherwise be possible. The movable belt being driven from the lower end thereof causes 35 the lower run of said belt to be in tension, thereby preventing slippage and buckling of the belt as the crusher is operated. By pivoting the belt along the same axis as the drive member for said belt, the driving of the belt 40 is unaffected as the supporting structure therefor swings to permit the boxes and other articles to pass between the belts. Both of the rollers for the two belts at the same end thereof being positively driven from the 45 same jack shaft insures the same operating speed for both belts, thereby eliminating slippage and abrasion of the belts.

Changes in the specific form of my invention, as herein disclosed, may be made within 50 the scope of what is claimed without departing from the spirit of my invention.

Having described my invention, what I claim as new and desire to protect by Letters Patent is:

55 1. A box crusher comprising a substantially horizontal belt, a framework straddling said belt, said framework including a superstructure, a shaft journalled in said superstructure, a plate extending between said framework and inclining downwardly toward said belt, bearings secured to said plate and journalled on said shaft, a roller carried by said shaft, bearings secured to the other end of said plate, a shaft journalled in said bearings, and a second roller mounted

on said shaft, and a belt extending over said rollers, said belt having a run thereof lying adjacent said plate.

2. A box crusher comprising a substantially horizontal belt, a framework straddling said belt and having a portion extending above the same, a shaft journalled in said framework above said belt, a subframe pivoted on said shaft, a roller mounted on said shaft, a second shaft journalled at the opposite end of said sub-frame, a second roller mounted on said second shaft, and a belt passing over said rollers, the second roller being weighted to force the free end of said second belt toward said first belt. 70

3. A box crusher comprising a substantially horizontal belt, a frame structure positioned above said horizontal belt, a shaft journalled in said frame structure, a sub-frame pivoted to said shaft and extending over said horizontal belt, the end of said sub-frame remote from said shaft being movable toward and from said belt, a second shaft disposed at the movable end of said sub-frame, rollers mounted on said shafts, a belt extending around said rollers, an auxiliary roller engaging said belt on the upper run thereof, and means for pivoting said auxiliary roller on said second named shaft, said auxiliary roller and said second named roller serving to weight said sub-frame to force the lower run of said second named belt toward the first named belt. 80

4. A box crusher comprising a carrier, a second carrier superimposing said first carrier and movable toward and from said first carrier, means for continuously urging said second named carrier toward said first named carrier, and means inoperative throughout the major portion of the movement of said carrier for retarding the movement of said urging means, said retarding means becoming operative upon the second carrier coming into close proximity to said first carrier. 90

5. A box crusher comprising a carrier, a second carrier superimposing said first carrier and movable toward and from said first carrier, a weighted member for urging said second named carrier toward said first carrier, and a spring inoperative throughout the major portion of the movement of said carrier for retarding the force of said weighted member, said spring coming into action upon the second named carrier coming into close proximity to said first carrier. 100

6. A box crusher comprising a carrier, a second carrier pivoted at one end to guide the other end thereof for swinging movement toward and from said first named carrier, a revolute member engaging the upper run of said swingable carrier, said revolute member being weighted to tighten said swingable carrier, said revolute member being disposed at the swingable end of said carrier to urge the same toward said first named carrier. 110

7. A box crusher comprising a carrier, a frame structure positioned above said carrier, an auxiliary frame pivoted at one end to said frame structure to cause the free end thereof to swing toward and from said carrier, a shaft at each end of said auxiliary frame, an endless carrier supported by said shafts, arms pivoted to the shaft at the free end of said auxiliary frame, a revoluble member pivoted in said arms, and adapted to engage said endless carrier, said revoluble member being weighted to simultaneously tighten said endless carrier and to move said frame structure toward said first named carrier.
- 5 8. A box crusher comprising an endless carrier, a second endless carrier superimposing said first carrier and having a shaft at each end thereof, means for pivoting said second endless carrier through said one shaft to cause the other shaft to move toward and from said first named carrier, a driving member loose upon said first named shaft, driving means secured to said second named shaft for driving said endless carrier, and means 10 for driving the driving means upon the first named shaft.
- 15 In testimony whereof I have affixed my signature to this specification.
- 20 NELS H. SANDBERG.
